UNITED STATES PATENT OFFICE.

THEODOR EMIL KREUTZER, OF PHILADELPHIA, PENNSYLVANIA, ASSIGNEE TO THE HOME COMFORT HEATER CO., OF PHILADELPHIA, PENNSYLVANIA, A CORPORATION OF NEW JERSEY.

GAS HEATER FOR FURNACES, STOVES, OR APARTMENTS.

Application filed September 13, 1922. Serial No. 527,889.

To all whom it may concern:

Be it known that I, THEODOR E. KREUTZER, a citizen of Germany (having resided in the United States one year last past), and having declared my intention of becoming a citizen thereof, residing in the city and county of Philadelphia, State of Pennsylvania, have invented a new and useful Gas Heater for Furnaces, Stoves, or Apartments, of which the following is a specification.

My invention consists of a device embodying a burner adapted to burn effectively commingled inflammable gas and air, the device being applicable in a furnace, stove or elsewhere, the construction of the device being such that the heat is generated in a large volume and of high temperature and adapted to be directed from the furnace, etc., into an apartment or apartments, the device obviating the use of coal, wood or other fuel, and the expense thereof, while also avoiding the usual attention to a furnace and the care of its ashes.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a top or plan view partly broken away of a gas burner embodying my invention.

Figure 2 represents a partial side elevation and a vertical section thereof.

Figure 3 represents a side elevation thereof on a reduced scale, showing also the outlines of a furnace in which the heater may be placed.

Figure 4 represents a section of a portion on line 4-4 Figure 2.

Similar numerals of reference indicate corresponding parts in the figures.

Referring to the drawings:

1 designates the base of the burner, the same being a hollow body of metal or other suitable material composed of the bottom plate 2 in the central portion of which is the air flue, 3, the wall of which forms the inner peripheral rim 4 which rises from said plate 2. Rising from the outer periphery of said plate is the exterior rim 5, said plate 2 and said inner and outer rims 4 and 5 thus forming an annulus.

On the top of the base 1 is the covering plate 6 which is rested on the rims 4 and 5 and secured to the bottom plate 2 by the bolts or screws 7 which pass through said plates and are provided with tightening nuts 8.

In the centre of said plate 6 is the opening 9 which is in communication with the flue 3. Connected with the side of the rim 5 is the gas supplying pipe 10 in the length of which is the air intake 11 whereby commingled gas and air are directed to the interior of the base as the receiver of the same, said pipe 10 being connected suitably with a source of supply of gas.

On the upper side of the plate 6 are tips forming gas burners 12 to which is directed fresh air in large volumes through the flue 3 and opening 9, said burner being supplied with commingled gas and air from the interior of the base 1 as is evident.

Above the base is the plate 13 of metal or other suitable material and above the latter is the plate 14 of metal or other suitable material, said plates being horizontally arranged separated from each other and from said base, and are secured in position by the bolts or screws 15 which pass through ears 16 on the plate 13, ears 17 on the plate 14, and ears 18 on the base, and tightened in position by nuts 19 whereby the plates 13 and 14 are held elevated firmly above the base.

In the plate 13 are the series of vertical perforations or flues 20 and in the plate 14 are the series of vertical ports, openings or flues 21 the parts being staggered in the two plates and are designed to allow the products of combustion and air to pass upwardly through the same and traverse the undersides of said plates respectively in zigzag direction from the sets of ports in the plate 13 to the sets of ports in the plate 14 and thus effectively heating said plates 14 and 13.

In the outer peripheral wall 5 of the body are the outlet ports 22 which lead from the interior of the body and allow the commingled gas and air to escape therefrom at the outer periphery of the body and to be consumed with that of the burners 12.

In the inner peripheral wall 4 of the body are the ports 23 which lead from the interior of the body and allow the commingled air

and gas to escape therefrom at the inner periphery of the body and to be consumed with that at the burners 12.

It will be seen that owing to the large volumes of gas and air supplied through the burners 12 and by the two courses respectively at the exterior and centrally of the body due to the ducts 22 and 23 when the gas is ignited at the burners, the products of combustion are impacted against the plates 13 and 14 and passed through the perforations of said plates thus intensifying the heat of the latter and as large volumes of air are furthermore supplied to the burning gas and air the resultant heat is of a large volume and of high temperature and so a perfect combustion is produced, the same being inodorous in its nature, thus obviating in apartments the objectionable smell or odor heretofore created in other gas heated devices of the class.

As the covering plate 6 is a separate member from the base it leaves the latter comparatively cool and so keeps the gas and air pipe 10 correspondingly cool. The perforations in the plates 13 and 14 allow the products of combustion to pass through them. This assisted by additional air which also enters said perforations increases the heat of said combustion thus greatly raising the temperature of said heat as it leaves the device and also consuming the fumes of the combustion whereby said fumes are destroyed.

35 The air intake 11 consists of a slotted valve plate 24 stationarily connected with the gas supply pipe 10 and a slotted valve plate 25 rotatively mounted on the neck 26 and placed against the outer side of said plate 24, so that by rotating said plate 25 the slots of the two plates may be placed in and out of register so as to adjust the amount of air admitted through the plate 24 and entering the pipe 10, or to cut it off 45 from the latter when so required.

The body of the device and its connected appurtenances will be supported in the furnace, stove, etc., in any suitable manner.

Having thus described my invention what 50 I claim as new and desire to secure by Letters Patent, is:—

1. In a gas heater, a hollow base comprising a bottom plate having centrally therein a vertical peripheral rim forming 55 a flue, and an exterior rim and a covering plate resting on said rims and secured to said bottom plate, said covering plate having centrally therein a flue coincident with said flue of the base and being provided with 60 gas burner orifices, said base having connected with it a gas supply pipe, perforated plates elevated above said covering plate, bolt-like members connected with said base

and rising therefrom and connected with said elevated plates, and tightening nuts adapting said plates to be supported separately from each other and from said base. 65

2. In a gas heater, a hollow base comprising a bottom plate having centrally therein a vertical peripheral rim forming a flue and an exterior rim and a covering plate resting on said rims and secured to said bottom plate, said covering plate having centrally therein a flue coincident with said flue of the base and being provided with gas burner 70 orifices, said base having connected with it a gas supply pipe, perforated plates elevated above said covering plate, said elevated perforated plates having ears peripherally thereon, bolt-like members in said ears, and tightening nuts on said members contiguous to said ears adapted to connect said elevated perforated plates with said base and support the former separate from each other and from said base. 75

3. In a gas heater, a body adapted to receive inflammable gas, the same being of the form of an annulus having outer and inner peripheral walls, a supply member for commingled gas and air connected with said body, a gas burner on said body, a plurality of perforated plates sustained above said burners, means passed through said plates and through the base of the body for supporting said plates in spaced relation, said body having therethrough an air flue formed by the inner peripheral wall of said body, said wall of said flue having therein gas outlet ducts leading from around the upper edge of the body, and the outer peripheral wall of said body having therein gas outlet ducts leading from around the upper edge of said body to said burner. 90

4. In a gas heater, a body adapted to receive inflammable gas, the same being of the form of an annulus having outer and inner peripheral walls, a gas supply pipe connected with the outer peripheral wall thereof, the inner wall thereof forming through the body an air flue, and a closing plate on the top of said body separate therefrom and resting on the top of the inner walls of said body and retained in position 100 on said body, said plate having therein an air passage which is in communication with said air flue, a plurality of separated plates above the closing plate, all of said plates having peripheral ears coincidentally arranged, and bolts passed through said ears and holding all of said plates in spaced relation. 105

THEODOR EMIL KREUTZER.
